NICHOLAS A. D'ARCY, OF LOS ANGELES, CALIFORNIA.

ORE-CONCENTRATOR.

1,369,899.

Specification of Letters Patent.

Patented Mar. 1, 1921.

Application filed October 5, 1918. Serial No. 257,811.

To all whom it may concern:

Be it known that I, JOSEPH W. McGALLIARD, a citizen of the United States, residing at 7619 Whitsett avenue, in the city of Los Angeles, county of Los Angeles, and State of California, have invented new and useful Improvements in Ore-Concentrators, of which the following is a specification.

An object of this invention is to provide 10 an ore concentrator that will produce better results than other ore concentrators heretofore known in the following particulars; viz., operation upon a larger amount of pulp for a given size machine, production of 15 cleaner concentrates and a larger percentage of savings.

This invention relates to that class of concentrators consisting in an inclined shaking table provided with cut-outs for the concentrates, leading down through the bottom of 20 the table, and this invention relates mainly to the construction and arrangement of the cut-outs and the table surface.

In machines of this kind the table slopes 25 somewhat from the head to the tail and the concentrates are taken out from the bottom of the table by means of a concentrates pipe which is arranged underneath a collector that is on the table surface and opens 30 toward the head of the table and is covered by a guard through which water is discharged through a pipe arranged under the guard and between the tail end of the table and the concentrates discharge device.

35 This invention relates to a novel construction and combination including the form and arrangement of the discharge surface, and the construction and arrangement of the guard and the concentrates outlet.

40 An object is to facilitate the delivery of concentrates to the collector; to facilitate the discharge of the concentrates in a regulable way without any danger of clogging, and to provide for a rapid and certain separation of the concentrates from the tailings at the inlet of the guard.

The invention is applicable with either water or air as the pulp enlivening medium.

Other objects, advantages and features of 50 invention may appear from the accompanying drawings, the subjoined detail description and the appended claims.

The accompanying drawings illustrate the invention.

Figure 1 is a side elevation of a concentrator constructed in accordance with this invention.

Fig. 2 is a plan of the same.

Fig. 3 is an enlarged inverted plan in section on line x^3 , Fig. 1. 60

Fig. 4 is an enlarged transverse section on line x^4 , Figs. 1, 2 and 3; some parts being omitted.

Fig. 5 is a plan on an enlarged scale of one of the cut-outs. 65

Fig. 6 is a longitudinal mid-section on line x^6 , Fig. 5.

Fig. 7 is a fragmental sectional detail on line x^7 , Figs. 5 and 6.

Fig. 8 is a grouped detail of the lip showing the same in plan, two end elevations and one side elevation. 70

Fig. 9 is a plan of the adjustable concentrator collector.

Fig. 10 is a sectional elevation on line x^{10} , Fig. 9, adjusted wide open. 75

Fig. 11 is a side view of one of the cut outs, on the same scale as Figs. 6 and 7.

The table is in the form of an elongate trough open at the top and at the tail end 80 and said table may be made of any suitable material, such as the wooden bottom 1 and wooden sluice walls 2 and 3, the weir 4 and the head box 5 with parts pertaining thereto.

The table is supported by any suitable 85 means as the springs 6 adjustably fixed at 7 to a support 8; said table being mounted upon said springs by the bearing 9 for allowing the table to be reciprocated endwise by the reciprocating mechanism 10. 90

In the form shown the table is illustrated as having two sluice-ways a , b , one extending from the weir to the tail between the walls 2 and 3 and the other extending from weir to tail between the wall 3 and the wall 95 $2'$; the walls 2 and $2'$ corresponding to each other and forming the side walls of the table, and the wall 3 forming a partition between the sluice ways.

The wooden bottom 1 of the table is provided in its surface with the shallow grooves 11, $11''$ that extend from weir to tail of the machine; each of said grooves being a slight depression, deepest at the longitudinal collecting mid-way c and sloping gradually 105 downward from each of the sluice-way side walls, so that the surface of the floor at each edge of the sluice walls is higher than

the mid-way surface *c* of the floor. The floor of each sluiceway is provided with a linoleum surface as at 12, 12" extending from the weir to the tail and conforming to the floor from sluice wall to sluice wall, so that the table surface from weir to tail is slightly deeper at the middle than at the edges, and the surface at the middle is flat and level and the surfaces at the sides thereof have a gentle decline from each sluice wall to the longitudinal collecting mid-way *c* of each sluice.

10 The water inlets 13 and concentrates outlets 14 are arranged with their axes intersecting the mid-line of the collecting surface and being normal thereto.

15 The collectors 15 are in the form of sheet metal members that are fastened to the surface table by collars 16 screwed down upon 20 the base flanges 17 at the tails of said collectors; each of said collectors having toward the head of the table from its flange 17, a raised and recessed body comprising the end wall 18, the side walls 19 and the 25 top 20.

Over each collector there is arranged a guard *G* open at the head end and closed at top, sides and tail. The collector 15 is spaced from its guard at the top allowing 30 between the top of the collector and the under side of the top of the guard, a free passage 21 through which the water or air, from the water pipe 13 may flow backward toward the mouth 22 of the guard. Said 35 guard is provided internally with the convex pressure deflecting cross bar 23 at a distance from the head edge 24 of the guard cover, and the separating table 25 projects beyond the head edge 24 of the guard and 40 toward the head of the table forming a central wash passage 26 down which the concentrates may flow along the mid-way and also forming an upper passage 27 just below the head edge 24 of the guard. Said separating 45 table has its tail edge *d* spaced apart from the head edge *e* of the pressure bar 23 to form a concentrates inlet 28 to the wash passage 26.

The collector is provided with side wings 50 29 fitting against the parallel sides of the guard walls 30, and the head ends of said wings 29 are arranged to form tailward converging walls 31 forming the flaring passage 32 leading also from and into the collector 55 chamber for the purpose of guiding the flow of water from the collector chamber simultaneously with the flow of concentrates into such chamber. Tailward converging riffles 33 extending obliquely downward along the 60 table surface from the side walls of the sluice-way to the head corners of the guard are provided for each cut-out and said riffles are somewhat deeper adjacent to the side walls than they are at the guards or cut-outs, 65 so that the current of pulp flowing down in

the sluice-way will be directed away from the sluice walls toward the mid-line of the table.

The concentrates discharge comprises the vertical pipe 34 projecting above the linoleum surface 12 and extending slightly above the linoleum surface at the lower portion or mid-way of the trough together with a bevel valve 35, the stem 36 of which extends down to the lower end of said pipe 34 and 70 is there reversely bent as shown at 37 and projects upwardly and has a screw threaded limb 38 arranged between two brackets 39, 40 through which the stem 38 passes. A nut 41 is screwed upon the stem 38 and acts 80 upon the spiral spring 42 and upon the lower bracket 39, the spring 42 being held down by the upper bracket 40, so that the operation of screwing the nut 41 in one or the other direction results in raising or lowering the 85 valve head 35 to bring its under bevel face to a higher or lower level. Said face terminates at the upper side in the sharp head edge 43, that may be adjusted close to the level of the top of the pipe or port 34 and 90 may be adjusted to a greater height within the bounds established by the top 15 of the collector. Said valve head 35 is circular in plan and is adapted to snugly fit the bore of the concentrates discharge pipe or port 34, 95 so that by lowering the valve until the charge 43 is on a level with the top end of the concentrates pipe 34, the outlet through said concentrates pipe will be shut off entirely. On the reverse movement the outlet between 100 the top end of the pipe 34 and the head edge 43 of the valve, opens; and said outlet is of greater horizontal width than the depth of the space below the bar 23 as it progresses inside so that any concentrates which may 105 find their way into the opening will pass freely from the cut out and will not clog, no matter to what fine outlet the concentrates charge may be adjusted.

The concentrates trough 44 extends from 110 head to tail of the table beneath the concentrates pipe 34 to receive the concentrates which may flow downward therefrom together with the wash water.

The collector may be variously constructed, and in the form shown in the drawings, the bar 23 and washing table 25 are connected by side pieces 26 formed integral with said bar, and table; and the head end of the guard proper is adapted to receive 120 the same and allow it to be inserted and removed without disturbing the main body of the guard which is fastened to the linoleum top by screws 45. The front end of the side walls of the guard are provided with notches 125 46 to accommodate the reduced end 47 of the inlet member formed of the table supporting bar and the side walls of the inlet.

The table is reciprocated endwise by any suitable head motion 48.

The pulp flows into the head box 5 through any suitable means as the trough 49, and the head box is provided with distributers 50, 51, in the form of staggered shelves downwardly sloping toward and away from the tail to deliver the pulp evenly through the weir from which it flows down onto the table.

The opposite edges *f* of the surface formed by the linoleum top at any cross sectional plane, are on a common level; but the head of the table top is slightly higher than the tail, so that as the table reciprocates end-
10 wise the contents thereof will be agitated by the converging riffles 33 and will have a gentle flow toward the tail and may be run in a stream of considerable depth depending upon the length of the table and the relative specific gravities of the mate-
15 rials to be separated.

It is evident that the heavier materials will settle most quickly, and that owing to the low grade of the sluice floors from end to end and the slope given by the mid-way of 20 the table, the heavier materials rapidly reach the mid-way. The pulp in practice fills the space between the converging riffles 33, and the gang may entirely cover said riffles and the guards; but the chambers of the guards 25 are kept free from the gang by the wash water supplied through the pipes 15 to the tails of the guard chambers, and flowing out at the heads of such chambers. The concentrates are shifted tailward underneath the 30 current of wash water by the reciprocation of the table.

Said wash water is regulable by the valves 52, and in practice the attendant may regulate the force of the wash water so as to exclude any particular specific gravity from 35 any particular collecting chamber beneath the guards. The wash water flows above the level of the collecting chamber and is thereby shunted over the inlet to said chamber and the upper portion of the stream of wash water flows out in a horizontal plane through the top outlet 53 and across the concentrates inlet 28, while another portion of the wash water is shunted by the 40 lower edge of the convex bar 23 downward across the path of the incoming concentrates which are given their impetus downward along the table by the reciprocating motion and the slight incline of the table. 45 The water is given a more forceful effect by the narrow bottom outlet or ejector throat 54, and passes therethrough with more force than through the upper outlet 53, and the wash water flows with less force past the 50 concentrates trap 28 and out through the inlet 26. The result of this is to pile the lighter material up at the front end of the guard whence it is floated off by the on-flowing water and tailings.

55 The water inlets 13 are supplied by the

piping system 55 that is secured by straps 56 to the bottom of the device as shown in Figs. 1, 3 and 4; and this piping system is connected by a flexible pipe 57 to a water supply not shown.

In practice the table may be adjusted at will to any desired pitch from head to tail, and to true transverse level at any pair of springs, by loosening the jam nuts 131 and turning the sockets 101 up or down 70 as may be necessary. Then the jam nuts will be tightened to maintain the adjustment.

The slanting under face of the valve 35 is at such an angle that when the valve is 80 fully open, the outlet is of larger dimensions than the depth of the ejector throat 54 so that any clogging of the concentrates may be relieved by opening the valve widely. No concentrates too large to pass the fully 85 opened valve outlet, can pass through the ejector throat 54.

It is understood that the fluid medium for enlivening the pulp and allowing gravity and inertia to effect the separation may be 90 either water or air under pressure introduced through the piping system 55 and in the case of compressed air, the pressure at the cut-outs is regulated by the valves 52 which serve to regulate the water in the op- 95 eration just described.

By making a free headward passage over the collector for fluid from the fluid inlet 13, the likelihood of clogging around the collector is avoided so that the concentrates 100 flow tailward into the collector beneath the fluid current. Said current flowing above and below the obstruction formed by the cross bar carries headward any tailings that may have passed the wash table and under 105 the head edge of the guard.

I claim:

1. In combination with the surface of a concentrator table, a concentrates collector open toward the head and closed toward the 110 tail of the table; a guard open at the head and closed at the top, sides and tail and forming a cover for the collector; the collector being spaced from the guard at the top allowing between the top of the collector and underside of the top of the guard a free passage through which fluid may flow toward the mouth of the guard; means to supply fluid to the tail of the collector so that it may flow over the collector toward 115 the mouth of the guard; said guard being provided internally with a convex transverse deflecting cross bar at the head edge of the guard; a separating table projecting beyond the outer head edge of the guard and 120 toward the head of the table, forming a center wash passage down which the concentrates may flow and also forming an outer passage just below the head edge of the 125 guard; said separating table having its tail 130

- edge spaced apart from the head edge of the transverse bar and forming a concentrates inlet to the wash passage.
2. In combination with a concentrator table surface, a collector having a chamber opening toward the head and closed toward the tail of the table, and a concentrates outlet opening downward; a valve head having a sharp head edge that may be adjusted to close the top of the concentrates outlet; said head being adapted to snugly fit the bore of the concentrates outlet and having its under face beveled downward toward the tail of the table.
3. In a concentrating table the combination with a concentrates collector and discharge, a guard therefor extending toward and open toward the head of the table, and means to supply fluid at the tail of the collector under the guard; a cross bar arranged under the head end of the guard and spaced from the guard and table surface to form passages above and below the cross bar.
4. In a concentrating table the combination with a concentrates collector and discharge, a guard therefor extending toward and open toward the head of the table, and means to supply fluid at the tail of the collector under the guard; a cross bar arranged under the head end of the guard and spaced from the guard and table surfaces to form passages above and below the cross bar; and a table located at the head end of, and spaced from the guard and from the table surface and also from the cross bar to afford free passages for concentrates, wash fluid and tailings.
5. In combination with a concentrator table surface and a guard having a chamber above such surface opening toward the head and closed toward the sides and tail of the table; a collector covered by said guard and being provided with side wings fitting against the inner sides of the guard walls; the head end of said wings being arranged to form tailward converging walls forming a flaring passage leading from and into the collecting chamber for the purpose of guiding the flow of fluid from the collecting chambers simultaneously with the flow of concentrates into such chamber; and tailward converging riffles extending obliquely tailward along the table surface to the head corners of the guard.
6. In combination with a concentrator table surface and a guard having a chamber opening toward the head and closed toward the sides and tail of the table; a collector provided with side wings fitting against the inner sides of the guard walls; the head ends of said wings being arranged to form tailward converging walls forming a flaring passage leading from and into the collector chamber for the purpose of guiding the flow of fluid from the collector chambers simul-

taneously with the flow of concentrates into such chamber; tailward converging riffles extending obliquely tailward along the table surface to the head corners of the guard; said riffles diminishing in height toward the guards so that a current of pulp flowing tailward on the table will be directed toward the collector and may completely submerge the riffles.

7. An ore concentrator table consisting of a slanting trough provided with sides and a middle wall extending the length of the trough, shallow grooves in the bottoms of the divided sections running the full length of the table and deepest midway in cross section; riffles in pairs extending from the walls downward, converging at the midway; in combination with collectors at such convergence; a guard which covers each of said collectors and is provided with a convex faced deflecting bar; a separating table projecting beyond the head of the guard; means for guiding concentrates thereto; means for flushing the trough; and resilient means for reciprocating the table.

8. In an ore concentrator table, the combination with a trough, a trough support, and means for agitating the trough; of downwardly converging riffles to a common center line; a collector at such convergence having a recessed body; a guard over the collector; means for admitting water between the top of the guard and the top of the collector; a convex faced deflecting cross bar in the guard; a separating table spaced apart from the said cross bar to form a concentrates inlet to a central wash passage formed by the head of the separating table, said table projecting beyond the head of the guard; there being water inlets and concentrates outlets, their axes intersecting the midline of the collecting surface.

9. An ore concentrating table comprising a trough, a collecting chamber in the trough provided with a recessed body open toward the head of the table; a guard over the collecting chamber, open at its head end and closed at its top, sides and tail, its top being spaced from the top of the collecting chamber to provide a free water passage to the mouth of the guard; a convex deflector in the guard; a separating table projecting beyond the head of said guard and spaced apart from the head edge of the deflector to provide a passageway below it for concentrates, and a passageway above it for water; converging walls connecting the sides of the collecting chamber with the sides of the guard and forming a flaring passage for the flow of water from, and concentrates into the collecting chamber; riffles in the trough to guide concentrates to the collecting chamber; valve outlets for concentrates in said collecting chamber; an inlet for water in the guard; means for supplying

water to the table; means for supplying ore to the table; and means for reciprocating the table.

10. In a concentrating table, in combination with a trough, riffles in the trough, a collecting chamber in the trough, a guard over the collecting chamber, a convex faced deflector in said guard; and means to supply ore and water to the trough; of an outlet in the collecting chamber, a valve in said outlet provided with a slanting under surface adapted to present a forward opening longer than provided by the guard deflector; and resilient means for control of 15 said valve.

11. In a concentrating table, a collecting chamber, a guard over said chamber, a convex pressure deflecting cross bar in said guard; and a separating table adjacent the 20 deflecting cross bar to provide an outlet for concentrates to the chamber.

12. In a concentrating table, in combination with a trough, a collecting chamber in the trough, of an inlet for concentrates 25 controlled by a convex deflector; and a valved concentrates discharge having its outlet larger than the inlet and adjustable to control the flow of concentrates from the collector.

30 13. In a concentrating table, a trough, a central level passage in said trough; a plurality of collectors in said passage; concentrates outlets in the collectors; a water supply means; means to regulate the water sup-

ply; means for directing the water flow 35 above the collectors and shunting it over the inlet to said collectors; convex bars adapted to deflect a portion of the water and to narrow and concentrate its flow to give it added force at its outlet; and means 40 to guide the gangue from the sides of the trough to the central levels and to the collectors.

14. In a concentrating table in combination with a trough, a collecting chamber, 45 and a water supply means; of a tubular outlet for concentrates, a valve seated in the top of the tube the underside of the valve being beveled upward toward the flow of the concentrates; a valve stem extending 50 down through the tube and bending around and upward outside of the tube and through two perforated lugs attached to the tube and spaced apart; a screw thread in the end of the stem; a nut on said threaded end and 55 between the lugs; a compression spring around the stem between the lugs and above the nut, and adapted to hold the valve closed normally, said valve to be opened and held open as wide as desired by an upward screwing of said nut.

In testimony whereof, I have hereunto set my hand at Los Angeles, California, this 25th day of September 1918.

JOSEPH W. McGALLIARD.

Witness:

JAMES R. TOWNSEND.
